AUTOMATIC COIN COUNTING AND WRAPPING DEVICE

Butler Sheldon, Jr., New York, N. Y., assignor to
Coin Counters Corporation, New York, N. Y., a
corporation

Application March 8, 1950, Serial No. 148,459

1 Claim. (Cl. 53—114)

1

This invention relates to a coin counting and wrapping device.

Broadly, it is an object of the invention to provide a simple device which will automatically count coins of the same denomination and which permits the coins to be wrapped.

More particularly, it is an object of the invention to provide a device which permits the automatic counting of coins and which is adapted to receive either a tube within which the coins so counted may be easily wrapped, or which can take an outside wrapper which permits the counted coins to be quickly and easily wrapped.

A further object of the invention is to provide a device which will permit either a tubular or a flat wrapper to be used to package a predetermined number of coins.

Another object is to facilitate the packaging of coins of uniform diameter, or denomination, each package containing a predetermined number of coins, which is the capacity of each operation of the device and which in that sense automatically counts the coins in every package.

The device is adapted to count and package coins of different denominations by varying the diameter and height of the tube for the different coins, such as pennies, nickels, dimes, quarters, half-dollars and dollars; the object being to rapidly count and package the well-known cylindrical packages of uniform coins by those, who in the course of their business, accumulate such coins in large numbers and wrap such coins in rolls for bank deposit, each roll representing a specific amount of money, for convenience in handling and counting.

Other advantages will become obvious and will be further described in the following specification.

For a fuller understanding of the nature and objects of the invention, reference is had to the following detailed description in connection with the accompanying drawing, in which:

Fig. 1 is a perspective view of the device.

Fig. 2 is a vertical longitudinal sectional view of the device shown in Fig. 1 with a column of coins of the same denomination therein.

Fig. 3 is a vertical longitudinal sectional view of the device shown in Figs. 1 and 2, showing a paper tube placed within the device prior to the feeding of coins therein.

Fig. 4 is a vertical sectional view of the device showing the paper wrapper in raised position after the coins have been placed therein to the top of the device.

Fig. 5 is a top view of the device shown in the previous figures.

Fig. 6 is a front view of the device having a column of like coins therein showing use of an outside paper wrapper for wrapping the column of coins.

2

Fig. 7 shows the outside paper wrapper wrapped around the tube containing the column of coins as shown in Fig. 6 with the upper end of the wrapper folded downward closing one end of the column of coins.

Fig. 8 shows the wrapped coins as shown in Fig. 7 with the device withdrawn from the column of coins and wrapper sealed at one end and ready to be sealed at the opposite end.

Referring to the drawings, numeral 10 represents a counting and wrapping device which comprises a base 11 and an open-ended tube 12 which is of thin metal. The base 11 is hollow, having a bottom 13 upon which the device rests and the tube 12 is firmly seated within the base 11 or is integral with it, as shown. Within the base 11 and rising into the tube 12, there is a platform member 14 which has a rounded upper end 15, concave sides 16 and a flat top or platform 17. The outer circumference of the rounded end 15 is somewhat spaced apart from the internal diameter of the tube 12. The base portion 13 of the platform member 14 is also spaced slightly apart from the internal diameter of the base 11. The upper end 20 of the tube 12 has a pair of opposed channels 19 for the purpose hereinafter described. The distance from the platform 17 to the upper end 20 of the tube 12 is the exact distance to receive a predetermined stack of coins of a given denomination. For example, if the tube is adapted to receive dimes, and it is desired to have five dollars in dimes counted, the space between the platform 17 and the upper end 20 of the tube 12 is the exact distance of the space occupied by an average column of fifty dimes stacked one upon the other so that in loading the dimes within the tube 12, by a slight movement of the device, any dimes above the upper edge 20 will move off the stack or the upper dimes above end 20 can be wiped off with the fingers, automatically leaving exactly fifty dimes within the tube 12.

A preferred paper tubular wrapper 21, of predetermined length, shown in Fig. 3, and of a height that will reach from the inner portion 22 of the bottom 13 to just below the upper end 20 and a diameter slightly less than the internal diameter of the tube 12, is then inserted within the tube 12 and between the stack of dimes and the internal diameter of the tube 12 to the inner portion 22 of the base so that the upper end 23 of the paper tube 21 is slightly below the upper end 20 of the counting tube 12.

The rounded upper end 15 and the curved base portion 13 will permit the bottom end 24 of the tube 21 to easily pass between the platform member 14 and the internal diameters of the tube 12 and base 11. The concave sides 16 are out of contact with the paper tube 21 and therefore offer no resistance to the passing of the tube 21. In

order to avoid air pockets, two fine channels 29 and 30 have been provided leading into the interior of the device. Of course, such channels may be placed in any desired portions of the device without interfering with its operation.

The paper tube 21 may be inserted within the counting tube 12 either before the dimes are placed within the tube 12, or after the dimes have been placed within the tube 12. However, it is preferable to place the paper tube 21 within the tube 12 before the dimes are inserted within the device 10. Since the upper end 23 of the paper tube 21 is below the upper end 20 of the counting tube 12, it is evident that the paper tube 21 will in no way interfere with an accurate counting of the coins within the tube 12 because the upper coin will be above the upper end 23 of the paper tube 21. When there is a full stack of coins within the tube 12 and within the paper tube 21, the index finger of the hand may then be placed upon the uppermost coin of the stack and the thumb and middle fingers may then draw up the paper tube 21 by inserting the latter two fingers within the opposed slots 19. The paper tube 21 is then lifted upwardly above end 20 to a height sufficient to permit the upper end of the paper tube 21 to be folded over the uppermost coin of the stack leaving sufficient paper below the bottom coin of the stack for folding over. Fig. 4 shows the paper tube 21 in a position so lifted before folding over the upper ends of said tube. Since the stack of coins presents a solid body with a comparatively sharp edge of the uppermost coin, it is easy to fold the end of the paper tube 21 over and upon the uppermost coin.

The device, including the stack of coins, is then reversed and the device is lifted off the paper tube 21 containing the column of coins therein in a manner similar to that shown in Fig. 8. Since the thin metal walls of the tube 12 provide a slight clearance, the coins, including the paper tube 21, will easily be separated from the tube 12 and thus permit the device to be easily lifted and separated from the paper tube 21 with the stack of coins therein. Since the platform 17 is above the bottom 24 of the paper tube 21, there will be sufficient paper to permit the lower end of the paper tube to be folded over the bottom coin, thus completely enclosing the stack of dimes or coins within the paper tube 21 in a package generally used by merchants in delivering wrapped coins to banks, or other institutions.

Referring to Figs. 6, 7 and 8 of the drawings, the device shown in such figures is the identical device shown in Figs. 1 to 5, inclusive. The wrapping of the stack of coins will now be described with an outside paper wrapper of the flat type, well known in commercial use. After the coins have been inserted between the platform 17 and the upper end 20 of the tube 12 so that an exact number of coins have been counted, a flat paper wrapper 25 which is wider than the stack of coins is wrapped around the outside of the tube 12 in a manner shown in Fig. 6. One longitudinal edge 26 is placed so that it rests upon the shoulder 27 of the base 11 with the body of the wrapper against the outer circumference of the tube 12, leaving the opposite edge 28 extending somewhat beyond the upper end 20 of the tube 12. After the wrapper 25 has been wrapped completely around the tube 12, the upper end of the wrapper 25 which extends above the stack of coins, is folded downwardly, as shown in Fig. 7. The device, including the stack of coins, is

then turned upside down. It will be noted that the platform 17 is higher than the edge 26 and shoulder 27 (see Fig. 6) so that when the device is turned upside down, the edge 26 of the wrapper 25 will be higher than the bottom coin which now has become the uppermost coin. Fig. 8 shows the device separated from the stack of coins within the wrapper 25. The opposite edge 26 of the wrapper 25 is then folded downwardly in a manner similar to that shown in Fig. 7 thus completely enclosing the stack of coins suitable and acceptable for deposit in the customary manner in banks.

It should be noted that in the use of the device, both with the tubular wrapper 21 and with the outside flat paper wrapper 25, that the end portions of the tube or wrapper when folded downward upon the stack of coins, will fold upon a hard surface of the face of the end coin so that at all times it will be easy to make a clean fold upon the ends of the stack of coins.

It is obvious that various changes and modifications may be made in the details of construction and arrangement of parts without departing from the general spirit of the invention.

I claim:

In combination, a coin counting and wrapping device, a hollow base having a bottom, a platform member fixed to said bottom within said base, said platform member having an upper flat top, a rounded upper edge and concave sides, a tube integral with said base and of the same internal diameter as said base, the said rounded edge of said platform member spaced slightly from the inner circumference of said tube and said base, a paper tubular wrapper insertable between said platform member and said tube, said paper wrapper of a length to reach from said bottom to just below the upper end of said tube, air channels in said base and platform member leading from the outer atmosphere into said device, the distance between said top of said platform member and the upper end of said tube being of a predetermined height to automatically count an average stack of coins of a given denomination placed within said device, opposed slots at the upper end of said tube for the fingers of the hand to draw up said paper tubular wrapper above the upper end of said tube, whereby the upper edge of said paper wrapper may be folded downward upon the upper coin of said stack of coins, the device and stack of coins reversed, the device withdrawn from said paper tubular wrapper and stack of coins, and the opposite end of said paper tubular wrapper may be folded upon the opposite end of said stack of coins completing a wrapped package of uniform coins of a predetermined value.
